AUTOMATIC REVERSING MECHANISM.

1,184,905.

Specification of Letters Patent. Patented May 30, 1916.

Application filed January 3, 1915. Serial No. 1,146.

To all whom it may concern:

Be it known that I, ALPHONZO WHITE, a citizen of the United States, residing at Worcester, in the county of Worcester and 5 State of Massachusetts, have invented certain new and useful Improvements in Automatic Reversing Mechanisms, of which the following description, in connection with the accompanying drawings, is a specification, like reference characters on the drawings indicating like parts in the several 10 figures.

This invention relates to reversing mechanisms such, for instance, as those employed 15 to control the movement of the work holding table of a metal planing or grinding machine.

The invention has among its objects to devise a mechanism of this general character 20 which shall be more positive in its action, more convenient to adjust, and less liable to get out of order, than those now used.

The invention will be readily understood 25 from the following description, when read in connection with the accompanying drawings, in which—

Figure 1 is a front elevation of a mechanism embodying the invention; Fig. 2 is a vertical, sectional view on the plane indicated by the line 2—2, Fig. 1; Fig. 3 is a front elevation showing, on an enlarged scale, a portion of the mechanism shown in 30 Fig. 1; Fig. 4 is a front elevation of an adjustable dog employed to operate the reversing mechanism; Fig. 5 is a vertical, sectional view on the plane indicated by the line 5—5, Fig. 4; and Fig. 6 is a rear elevation of the plunger used in the dog shown in Figs. 4 and 5.

40 Referring now to the drawings, 2 indicates the frame or bed of a machine, such for instance as a grinder or planer, provided on its upper face with horizontal ways on which slides a table 4 that is designed to 45 carry the work. This table is reciprocated on its ways to present different portions of the work to the operation of the grinding or other tool. For this purpose a rack 6 is secured rigidly to the bottom of the table extending parallel to the ways on which the 50 table slides, and a pinion 8 meshes with this rack and is mounted on the upper end of a vertical shaft 10 supported in suitable bearings in the frame 2. Mounted on the shaft 10

is a toothed clutch sleeve 12 keyed to the shaft 55 but slideable longitudinally thereof into or out of engagement with a similar toothed sleeve 14 that rotates loosely on the shaft 10 and forms the hub of a worm wheel 16. In order to move the sleeve 12 into or out of engagement with its coöperating sleeve 14, a collar 18 is formed on the sleeve 12 and is grooved to receive a pair of rolls 19 and 20 mounted on the forked end of a lever 22 which is fulcrumed on the machine frame at 60 23. The forward end of this lever is positioned within convenient reach of the operator.

The worm wheel 16 is driven by a worm 24 which is fast on one end of a shaft 25 70 mounted to rotate in a long bearing formed in one part of a gear casing 26 that is bolted to the side of the machine frame 2. A large bevel gear 27 is mounted on the forward end of the shaft 25 and within the casing 26. The main driving shaft 28 of the machine is mounted in bearings formed in the casing 26 and has secured thereto a series of pulleys 29 by means of which the machine may be belt connected to any convenient source of power. Within the casing 26 the shaft 28 supports two bevel gears 30 and 31, respectively, which are arranged to mesh with the bevel gear 27 at opposite points in its periphery. Both of these gears 30 and 31 are loose on the shaft 28 and the adjacent ends of their hubs are toothed. A sleeve 32, mounted on the shaft 28 between the gears 30 and 31, and splined to said shaft but slideable thereon, has its opposite ends 75 toothed to mesh with the teeth on the respective gears 30 and 31. Accordingly, when this sleeve is moved into engagement with either one of the bevel gears 30 or 31, it will cause the gear so engaged to rotate with the 80 shaft 28 and this rotative motion will be transmitted to the bevel gear 27 and through the shaft 25, worm 24, worm wheel 16, the clutch members 12 and 14 (assuming them 85 to be in engagement) shaft 10, pinion 8 and rack 6, to the table 4. The direction of this motion will depend on which of the gears 30 or 31 is driving the bevel gear 27.

For the purpose of controlling the engagement of the clutch sleeve 32 with one 90 or the other of its coöperating gears 30 and 31, this sleeve is grooved to receive a member 95 forming part of a shoe 34 which is

pinned to a rod 36 lying above and parallel with the shaft 28 and is arranged to reciprocate longitudinally in bearings formed in the casing 26. This rod 36 has pinned to it at opposite ends of the shoe 34 two stop collars 38 and 39, respectively. When the rod 36, carrying the stops or collars 38 and 39 and the shoe 34, is moved far enough in one direction or the other to effect a driving engagement between the clutch sleeve 32 and one of the gears 30 or 31, it is locked in that position by one member of a pair of pawls 40 and 41, pivoted, respectively, near the opposite ends of the rod 36, the pawl 40 being arranged to engage with the collar 38, and the pawl 41 with the collar 39. Two springs 42 and 43 connected to the respective pawls 40 and 41 serve to retain them yieldingly in locking engagement with their respective collars.

The pawls 40 and 41 may be released from locking engagement with their respective collars by means of a lever 44 fulcrumed on the upper part of the casing 26 and having a handle that projects above the level of the work table 4 and a part projecting below the fulcrum and carrying a pin 46 that lies between adjacent ends of the pawls 40 and 41. The ends of these pawls lie close to each other and are curved upwardly, as shown clearly in Figs. 1 and 3, so that, when the pin 46 is swung into engagement with either pawl, it will lift it out of engagement with its coöperating stop collar 38 or 39.

Pivoted to the rear face of the lever 44, and just below the fulcrum of said lever, are two arms indicated at 48 and 49, which bow out away from each other, then curve inwardly and downwardly toward each other again, terminating in ends that lie on opposite sides of a pin 50 that projects rearwardly from the shoe 34. The pin 46 extends through the end of the lever 44 and the portion of the pin 46 that projects from the back of the lever 44 also lies between the ends of the arms 48 and 49 and just above the pin 50. A coiled spring 52 has its ends connected to the bowed portions of the arms 48 and 49 and tends to keep the free ends of the arms 48 and 49 in contact with the pins 50 and 46.

While the lever 44 may be moved in either direction by hand, ordinarily this movement is effected automatically by adjustable dogs mounted on the table 4. A dog of novel construction is provided by this invention. In the arrangement shown, a rack 54 is secured to the edge of the table 4, the teeth of this rack projecting downwardly. The dog 56 has a body 56 straddling the rack 54 and designed to slide freely along the rack. This body 56 is drilled vertically to receive a plunger 58 which has a flat face 59 (see Fig. 6) designed to slide along the plane side of the rack 54, and is provided at its lower end

with a small toothed stop 60, the teeth of the stop being shaped to fit into the teeth of the rack. At its upper end the plunger 58 has secured thereto a cap 62 which is of larger internal diameter than the plunger, thus providing an annular place around the plunger in which is seated a coiled spring 64 that bears against the inner face of the cap and the top of a boss 66 formed integral with the body 56 and on which boss the cap 62 slides. In other words, the cap 62 forms a housing or inclosure for the spring 64.

It will be evident from an inspection of Figs. 4, 5 and 6 that the spring 64 normally presses the plunger 58 upwardly and holds the teeth of the part 60 in mesh with the teeth of the rack 54, thus locking the dog against movement longitudinally of the rack. When it is desired to adjust the dog it is merely necessary to depress the plunger sufficiently to move the teeth 60 out of engagement with the teeth of the rack and then to slide the dog along the rack the required distance. This construction prevents the entrance of dirt into the moving parts, is very easily operated and since the teeth of the rack project downwardly they cannot get filled up with chips or other foreign material.

A stop 68 is pivoted to the body of the dog 56 on a screw 69 and the forward depending end of this stop is positioned for engagement with a pin 70 projecting from the rearward side of the lever 44. The rack 54 of course carries two dogs 56, one on each side of the lever 44, one of these dogs serving, by the engagement of its stop 68 with the pin 70, to move the lever 44 in one direction and the other to move the lever in the opposite direction. In order to obtain a finer adjustment of the stop with relation to the table 4 than could be made by means of the plunger 58, the part 56 has projecting therefrom an ear 72 through which is threaded an adjusting screw 74 arranged to bear against the back of the stop 68 and to swing this stop more or less about its pivot 69 to give any required adjustment of the stop. A lock nut 76 serves to hold the set screw 74 in adjusted position.

It is sometimes necessary to lift the stops 68 into such a position that they will clear the pin 70 on the lever 44 and in order to permit the workman to make this adjustment and leave his hands free for other work, a friction device is provided to hold the stop yieldingly in any position to which it may be moved. This device consists in the construction shown of a spring 78 seated in a small hole formed in the body 56 of the dog and a ball 80 that is pushed against the rear face of the stop 68 by the spring 78. This arrangement affords sufficient friction to hold the stop 68 in any position of

adjustment to which it may be moved with reference to the body 56.

It will now be clear that, when the main shaft 28 is being driven, if the lever 44 is 5 swung out of its neutral position far enough to cause the clutch sleeve 32 to engage one of the gears 30 or 31, the table will be moved along its ways through the connections previously described. Assuming the lever to 10 have been thrown to the right as the parts are seen in Fig. 3, thus moving the clutch sleeve 32 into engagement with its coöperating clutch part formed on the gear 31, as shown in said figure, the table will be 15 moved from right to left. The pawl 40 at this time will be in engagement with the stop collar 38, thus holding the parts 31 and 32 in operative engagement. When the table has moved to a point predetermined 20 by the adjustment of the right hand dog 56, as the parts appear in Fig. 1, the stop 68, carried by the dog, will strike the pin 70, thus swinging the lever 44 toward the left and moving the pin 46, mounted on the 25 lower end of the lever, toward the pawl 40. The spring 52, acting through arms 48 and 49, tends to hold the pin 50 in line with the fulcrum of the lever 44 and the pin 46 and, consequently, normally tends to hold 30 the clutch sleeve 32 in an intermediate or neutral position between the gears 30 and 31 where neither gear will be driven. Since the shoe 34 controls the position of the clutch sleeve 32, it controls the direction 35 of movement of the table 4.

The initial movement of the lever 44, as above described, to render operative the gear 31 tensions the spring 52 in a direction tending to move the clutch sleeve 32 back 40 toward its neutral position. The movement of the lever 44 produced by the dog 56, as just described, further tensions this spring 52 in the same direction since the pin 46, in swinging toward the pawl 40, moves the 45 arm 48 in a counter clock-wise direction, as the parts are seen in Fig. 3. Consequently, as soon as the pin 46 has been moved far enough to release the pawl 40 from engagement with the collar 38, the spring 52 then 50 operates through the arm 49, the pin 50 and the shoe 34 to slide the clutch sleeve 32 out of engagement with the gear 31 and into engagement with the gear 30. The latter gear then becomes operative to drive the 55 table 4 in a direction opposite to the direction in which it has just been driven by the gear 31. The pawl 41, by its engagement with the collar 39, holds the clutch 32 in operative engagement with the gear 30. The 60 entire operative portion of the spring 52, which in the present instance includes all of the spring between the pins on which it acts, is effective to shift the shoe 34, and consequently the clutch sleeve 32, from either one 65 of its operative positions to the other.

When the dog 56 at the left of the lever 44 strikes the pin 70 and swings the lever 44 to the right again, the spring 52 will be tensioned in a direction opposite to that in which it has just acted, the pawl 41 will be 70 lifted and the sleeve 32 will be moved by the spring 52, operating through the arms 48, into engagement with the gear 31. This cycle of operations will be repeated until interrupted by moving the clutch sleeve 32 75 through the means of the lever 44 into a neutral position or by the interruption of the driving connections between the gear 27 and the table 4 by depressing the forward end of the clutch lever 22 and throwing the 80 clutch members 12 and 14 out of engagement with each other. One advantage of this arrangement is that the same spring effects the shifting of the sleeve 32 in both directions, thus avoiding a difficulty which 85 has heretofore been experienced with similar mechanisms in which independent springs are used to throw the clutch part in opposite directions and in which it was found that the reversing mechanism often 90 failed to work due to one spring being stronger than the other. The present mechanism also is of advantage because of the saving in parts which it effects.

Having fully described my invention, what 95 I claim as new and desire to secure by Letters Patent of the United States is:

1. In a machine of the character described, the combination with a driving shaft and a reciprocatory table, of means 100 arranged to be operated by said shaft for giving said table a reciprocating movement, a reversing mechanism controlling the operation of said means, said mechanism comprising a device for controlling the direction of movement of the table and movable from one position to another to effect a reversal of the movement of the table, means for locking said device temporarily in either of said positions, a tension spring connected 105 with said device to move it from either one of said positions to the other, the same portion of said spring being operative to move said device in both directions, and means operative at predetermined points in the 110 stroke of the table to release said locking means whereby said spring will move said device from one of said positions to the other.
2. In a machine of the character described, the combination with a driving shaft and a reciprocatory table, of means 115 arranged to be operated by said shaft for giving said table a reciprocating movement, a reversing mechanism controlling the operation of said means, said mechanism comprising a device for controlling the direction of movement of the table and movable from one operative position to another to 120 effect a reversal of the movement of the table,

a tension spring connected with said device to move it from either one of its operative positions to the other, means for locking said device temporarily in either of its operative 5 positions, and means operative at predetermined points in the stroke of the table to tension the entire operative portion of said spring in a direction depending on the direction of movement of the table and to 10 release said locking means, whereby said spring will move said device from one of its operative positions to the other.

3. In a machine of the character described, the combination with a driving 15 shaft and a reciprocatory table, of two members arranged to be driven by said shaft and having connections with said table enabling them to drive the table in opposite directions, a clutch device arranged to occupy a 20 neutral position or to be moved into different operative positions to render one or the other of said members operative to drive said table, and means for operating said device comprising a tension spring, means operated 25 by said spring to hold said device yieldingly in its neutral position, means for locking said device in either of its operative positions, and means operated by the table for tensioning the entire operative portion of 30 said spring alternately in opposite directions and then releasing said locking means to permit said spring to move said device from one operative position to another.

4. In a machine of the character described, the combination with a driving shaft and a reciprocatory table, of means arranged to be operated by said shaft for giving said table a reciprocating movement, a reversing mechanism controlling the operation of said means, said mechanism comprising a device for controlling the direction of movement of the table and movable from one operative position to another to effect a reversal of the movement of the table, means 45 for locking said device temporarily in either of its operative positions, a tension spring, means connected with the opposite ends of said spring for transmitting the action of said spring to said device, and mechanism 50 operative at predetermined points in the stroke of said table to tension said spring in a direction depending on the direction of movement of said table and to release said locking means, whereby said spring will 55 operate through said transmitting means to move said device from one of its operative positions to the other.

5. In a machine of the character described, the combination with a driving shaft 60 and a reciprocatory table, of a pair of gears arranged to be driven by said shaft and having connections with said table enabling them to drive the table in opposite directions, a clutch device mounted for movement into either of two positions operative

to render one or the other of said gears effective to drive said table, a pair of movable arms operatively connected with said device to move the device from one position to another, a spring connecting said arms and tending to hold said device in a neutral 70 position, means for locking said device temporarily in either of its operative positions, and a lever arranged to be oscillated by said table and operating through said arms to tension said spring in either direction and thereafter to release the locking means to permit the spring to move said device from either of its operative positions to the other. 75

6. In a machine of the character described, a table, a rack secured to said table with its teeth projecting downwardly, a dog slideable on said rack, and means carried by said dog operative through engagement with the teeth of said rack to lock 80 said dog against movement along the rack and to be released again to permit the adjustment of the dog along the rack. 85

7. In a mechanism of the character described, a rack supported with its teeth projecting downwardly, a dog slideable on said rack, a device constructed to interlock with the teeth of said rack, said device being carried by said dog but movable relatively thereto into or out of engagement with said teeth and operating to hold the dog against movement along the rack when in engagement with said teeth, and means for normally holding said device in locking engagement with the teeth of said rack. 90 95

8. In a mechanism of the character described, a rack supported with its teeth projecting downwardly, a dog slideable on said rack, a plunger vertically movable with relation to said dog and rack but slideable with 100 said dog, said plunger being provided with a part constructed to interlock with the teeth of said rack, and a spring operating on said plunger to hold said part normally in engagement with said teeth. 105

9. In a mechanism of the character described, a rack supported with its teeth projecting downwardly, a dog slideable on said rack, a plunger mounted in said dog to slide therewith but movable vertically in said dog, 110 said plunger having a part arranged to interlock with the teeth of said rack when the plunger is raised, a cap fast on the upper end of said plunger, and a spring between said cap and dog operating to hold the 115 plunger yieldingly in its raised position, said cap being shaped to inclose said spring. 120

10. In a mechanism of the character described, an adjustable dog, a stop supported by said dog for adjustment relatively 125 thereto, and friction means for holding said stop yieldingly in an adjusted position with relation to said dog.

11. In a machine of the class described, the combination of a driving shaft, a recip- 130

rotating table, reversing mechanism, connections between said shaft and table controlled by said mechanism for driving the table, a dog adjustably mounted on said table, said reversing mechanism including a member arranged to be operated by said dog, a stop pivoted on said dog for movement into or out of position to engage said member and a friction device interposed between adjacent surfaces of said dog and stop operative to hold the stop yieldingly against movement relatively to the dog. 10

In testimony whereof I have affixed my signature in presence of two witnesses.

ALPHONZO WHITE.
